Mac L. Schmid
Att'y

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

CUTTER CHAIN.

Application filed March 6, 1919. Serial No. 281,029.

To all whom it may concern:

Be it known that I, MORRIS P. HOLMES, a citizen of the United States, residing at Claremont, in the county of Sullivan and 5 State of New Hampshire, have invented certain new and useful Improvements in Cutter Chains, of which the following is a full, clear, and exact specification.

My invention relates to cutter chains.

10 It has for its object to provide an improved cutter chain, and more especially, while not limited thereto, an improved cutter chain adapted to use on a mining machine. A further object of my invention 15 is to provide an improved link in such a chain whereon a cutter bit or a plurality of the same may be carried in an improved manner and adjusted into a plurality of cutting positions at the same time that an 20 exceedingly simple, positive, and rugged construction is retained. These and other objects and advantages of my improved construction will, however, hereinafter more fully appear.

25 In the accompanying drawings I have shown for purposes of illustration several embodiments which my invention may assume in practice.

In these drawings,—

30 Fig. 1 is a side elevation, partially in section, showing a cutter chain constructed in accordance with my improvement.

Fig. 2 is a partial plan view of the same.

Fig. 3 is a sectional view taken on line 35 3—3 of Fig. 1.

Fig. 4 is a sectional view of another form of my invention, wherein a plurality of bits is carried by a single link.

Fig. 5 is a plan view of this form of 40 the same.

Fig. 6 is a detail sectional view taken on line 6—6 of Fig. 4.

Fig. 7 is a perspective of the adjustable locking member.

45 Fig. 8 is a perspective of another form of said member.

In this illustrative construction it will be observed that the cutter chain includes a plurality of sets of links 1 and 2, each 50 set herein being pivotally connected at 3. As shown, the links 2 alternate with the links 1 and are the cutter links or cutter carrying elements, although obviously any desired arrangement or sequence of links 55 may be used.

In my improved construction the links 2 are provided with upwardly disposed integral extensions 4 having longitudinally disposed recesses 5 therein, these recesses herein being shown as of cylindrical cross 60 section. In these recesses are disposed cylindrical extensions 6 on eccentrically disposed cylindrical locking members 7. As shown, these extensions 6 are provided with threaded bores 8 adapted to receive screws 65 9 the shanks of which extend through suitable registering apertures 10 in the vertical wall of the member 4 so that when the heads 11 on the shanks of the screws 9 are adjusted the members 7 may be rigidly clamped 70 to the members 4. In my improved construction, it will also be observed that the members 7 are slotted transversely, as at 12, the slot, as herein, preferably extending also through the inner end of the extension 6. 75 Attention is also directed to the fact that the inner edge of the member 4 is provided with a plurality of slots 13, which may be provided in any desired relation or number, herein three, and relatively inclined, one 80 being disposed vertically and the others being disposed angularly on opposite sides of the same. As shown, these slots 13 are adapted to register with the slot 12 in the member 7 in different rotary positions of the 85 latter relative to the member 4, and cooperate with the slot 12 in forming a plurality of slots adapted to receive a usual cutter bit 14. As a result of this construction, it will be noted that, as shown in Fig. 3, the bit 90 may be placed in any desired position of a plurality of positions, and that the same is adjustable longitudinally of the cooperating slots or freely removable therefrom when the screw 9 is released, and clamped 95 firmly in position when this screw is tightened. Attention is here also directed to the fact that the sides of the links 2 are cut away, as shown at 15, in such a manner as to permit free lateral movement of the inner ends of the cutter bits as the latter are adjusted angularly relative to the member 4.

In Figs. 4 to 7 of the drawings it will be noted that I have illustrated another 105 form of the invention just described. In this construction, it will be observed that the cutter bit carrying link 16 is provided with an elongated, upwardly extending cylindrical portion 17, transversely slotted at 18 at 110

a point between its ends and having a longitudinal bore 19 adapted to receive an elongated cylindrical member 20 having a clamping shoulder 21 on its rear end and adapted 5 to be adjusted longitudinally by means of a screw 22 similar to the screw 9 heretofore described and threaded into the member 20 in the same manner. In this construction, it will be observed that an intermediate tubular member 23 is disposed in the slot 18 upon the member 20, and that this member 23 is provided with a plurality of transverse slots, herein shown at 24 and 25, on the opposite ends thereof and disposed at an angle one 10 to the other, herein at right angles, although obviously the number and the angles of the slots may be varied as desired. In this construction it will be observed that the member 20 is also slotted transversely at 15 26 by intersecting V-slots, as shown in Fig. 6, in such a manner as to enable the shanks of the cutter bits to pass therethrough between oppositely disposed longitudinally extending portions 27 thereof of V-shaped cross section. As a result of this construction, it will be observed that a plurality of bits may be used, one bit being adjustably but firmly clamped in the slot 24 and the other similarly clamped in the slot 25 as 20 the screw 22 is adjusted in one direction, and both bits being released when the screw is turned in the opposite direction. It will also be observed that due to the positive clamping action of the member 20, slots in 25 the member 17 which correspond to the slots 18 may be omitted under certain circumstances if desired.

In Fig. 8 I have illustrated a form of construction of one of the elements of a chain 40 of the general type just described which is adapted to use with the other elements thereof to provide a wider range of adjustment. In this construction, it will be noted that the member 23 is divided transversely into 45 two parts 28, 29, each having a serrated edge 30. As a result of this construction, it will be observed that an even wider variation in adjustment may be obtained by simply varying the position of one of the members 28, 29 relative to the other. It will also 50 be noted that in each position the parts are securely clamped, the serrated portions interlocking and the clamping means being of the same construction as described above.

55 By my improved construction, it will be observed that a wide variety of positions of a cutter bit may be obtained by simply adjusting the slotted bit carrying or receiving member relative to its support. It will also 60 be observed that by adjusting different bits in successive cutter links into different angular positions, or by turning certain of the adjusted bits end for end, a cutter chain having a wide range of bit positions may be 65 produced with cutter links of a single con-

struction, all special links being rendered unnecessary. In certain forms of my improved constructions, it will also be observed that a plurality of bits may be similarly adjusted in a single cutter link, and that through a 70 simple rotary adjustment of the bit carrying or receiving means included in the chain, or a reversal of the same, a wide variation in the positions of a two-bit link chain may be obtained. Attention is also directed to 75 the fact that at the same time that these various adjustments make it possible to change the position of the cutter bits and thereby vary the effect of the chain, it is also possible to clamp the bits rigidly in 80 each of their operative positions and remove the same from the chain for sharpening or the like, with great facility and whenever desired. Attention is also particularly directed to the fact that my improved construction is of an exceedingly rugged and 85 simple character adapted to long life in service. These and other advantages of my invention will, however, be clearly apparent to those skilled in the art. 90

While I have in this application specifically described certain specific embodiments which my invention may assume in practice, it is to be understood that these forms are shown for illustrative purposes only and that the invention may be modified to assume various forms without departing from its spirit or the scope of the appended claims. 95

What I claim as new and desire to secure by Letters Patent is: 100

1. In a cutter chain, a cutter link having a lateral extension thereon, and means for rigidly clamping a plurality of cutter bits thereto each in a plurality of angular positions. 105

2. In a cutter chain, a cutter link having a lateral extension thereon, and means for rigidly clamping a plurality of cutter bits thereto, one in a plurality of angular positions relative to the other. 110

3. In a cutter chain, a cutter link having a lateral extension thereon, and means for rigidly clamping a plurality of cutter bits thereto at a plurality of different angular positions relative to each other. 115

4. In a cutter chain, a cutter link having a lateral extension thereon, and means including an adjustable slotted bit receiving member for rigidly clamping a plurality of straight shanked cutter bits thereto in a plurality of angular positions. 120

5. In a cutter chain, a cutter link having a lateral extension thereon, and means for clamping a plurality of laterally disposed straight shanked cutter bits thereon including a transversely slotted angularly adjustable member. 125

6. In a cutter chain, a cutter link having a lateral extension thereon, and means for clamping a plurality of laterally disposed 130

- cutter bits thereto including bit receiving means having transverse bit receiving slots opening through the opposite end surfaces thereof.
5. 7. In a cutter chain, a cutter link having a lateral extension thereon, means for clamping a plurality of laterally disposed cutter bits thereto including bit receiving means having transverse bit receiving slots at the 45
- 10 opposite ends thereof, and means whereby the angle between said slots may be varied.
8. In a cutter chain, a cutter link having a transversely slotted lateral extension thereon, a rotatively adjustable member disposed in the slot therein and having transversely extending cutter bit slots and means for rigidly clamping said member to said extension.
- 15 9. In a cutter chain, a cutter link having a transversely slotted lateral extension thereon, an adjustable member disposed in the slot therein and having transversely extending cutter bit slots, and means for rigidly clamping said member to said extension in any one of a plurality of different angular 50
- 20 positions.
10. In a cutter chain, a cutter link having a longitudinally bored lateral extension thereon, a transversely slotted member receivable in said bore, and cooperating means extending through said slotted member and into said bore for rigidly clamping said member to said link in a plurality of different angular positions.
- 25 11. In a cutter chain, a cutter link having a transversely slotted lateral extension thereon, a transversely slotted member receivable in the slot therein and insertable therein and removable therefrom by rectilinear movement perpendicular to the longitudinal axis of said link, and means extend- 55

- 45
- 50
- 55
- 60
- 65
- 70
- 75
- ing axially of said extension and said member for rigidly clamping said member to said link.
12. In a cutter chain, a cutter link, a plurality of cutter bits, a mounting therefor in said link comprising means for adjusting one of said bits angularly relative to another, and means for rigidly clamping said elements.
13. In a cutter chain, a cutter link, a plurality of cutter bits, means including interlocking elements for adjusting one of said bits angularly relative to another, and means for clamping said elements together.
14. In a cutter chain, a cutter link, a plurality of cutter bits, means including interlocking, serrated, transversely slotted elements for adjusting one of said bits angularly relative to another, and means for clamping said elements together.
15. In a cutter chain, a cutter link having a lateral extension thereon, a plurality of bits mounted in said extension and arranged so that their projections on a plane perpendicular to the direction of travel of said link make an angle, and means whose axis passes through the apex of said angle for clamping said bits to said link.
16. In a cutter chain, a cutter link having a lateral extension thereon, a plurality of bits mounted in said extension in longitudinally spaced relation and arranged so that their projections on a plane perpendicular to the direction of travel of said link make an angle, and coaxially arranged elements controllable wholly from one end of said link for clamping said several bits to said link.

In testimony whereof I affix my signature.

MORRIS P. HOLMES.
